Platt L. Ingeroll

UNITED STATES PATENT OFFICE.

PLATT C. INGERSOLL, OF GREEN POINT, NEW YORK, ASSIGNOR TO HIMSELF AND H. F. DOUGHERTY, OF SAME PLACE.

IMPROVED MODE OF FASTENING DOORS OF HAY AND COTTON PRESSES.

Specification forming part of Letters Patent No. **38,928**, dated June 16, 1863.

To all whom it may concern:

Be it known that I, P. C. INGERSOLL, of Green Point, in the county of Kings and State of New York, have invented a new and useful Improvement in Fastening Doors of Hay, Cotton, and other Presses; and I do hereby declare that the following is a full, clear, and exact description of the construction and operation of the same, reference being had to the annexed drawings, making a part of this specification, in which—

Figure 1 is a longitudinal elevation of the top section of a press; Fig. 2, a plan view of the top of a press.

A is the frame of a press.

B are doors upon either side of a press, as shown in Fig. 2.

C are rods, straps, or levers hinged at D to the doors B.

E are staples or eye-holes, which levers or straps C enter to hold the doors closed under great pressure.

F are spring catches or latches to secure and hold levers C in contact with the doors to keep them closed, and to readily release them under great pressure. Projections G upon the inner sides of the doors B hold the siding H in the exact position required while a bale is being pressed.

I are levers, rods, or straps hinged at J to the hinged ends of doors B. Levers I have projections K, which securely hold siding L up in the position required while a bale is being pressed.

M is a lever hinged at N, it acts as a fastener to keep levers I and their projections K in contact with siding L.

O is the cover or top door. It is secured in position (when a bale is being pressed) with stirrups P, and can be readily and easily opened by lever Q.

Operation: Open the top or door O, (as this press is intended to be used with a follower working upward;) fill the press with the material to be pressed; close the door O, the two doors B also being closed, (the kind of press to which this is a part being attached, and which is more fully described in another application that accompanies.) The press is then operated to press or compress the bale. The doors B, or one of the said doors, are opened by actuating the spring catch or latch F, thus releasing rod C. At the same time move lever M in the direction shown by the arrow, thereby releasing levers I. The bale can be then fastened by any of the known ways, and conveniently removed from the press.

What I claim as my invention, and desire to secure by Letters Patent, is—

1. The levers C, attached to the doors of a press, with their fastenings E and F, as and for the purpose described.

2. The levers I and their mode of hanging, fastening, and operating, as and for the purpose specified.

3. The projections G, for the purpose described.

PLATT C. INGERSOLL.
